UNITED STATES PATENT OFFICE

EDWARD T. MALLOY, OF HAMILTON, OHIO

DESIGN FOR A CASTER

Application filed March 11, 1930. Serial No. 34,820. Term of patent 14 years.

To all whom it may concern:

Be it known that I, EDWARD T. MALLOY, a citizen of the United States, residing at Hamilton, in the county of Butler and State of Ohio, have invented a new, original, and ornamental Design for Casters, of which the following is a specification, reference being had to the accompanying drawing, forming part thereof.

The figure is a perspective view of a caster, showing my new design, the ornamentation upon which extends upon the opposite side, thereof substantially as shown in the drawing.

I claim:

The ornamental design for a caster, as shown and described.

EDWARD T. MALLOY.
